HINGE FOR REFRIGERATOR DOORS

Edmund F. Schweller, Dayton, Ohio, assignor to
General Motors Corporation, Dayton, Ohio, a
corporation of Delaware

Application September 28, 1937, Serial No. 166,198

1 Claim. (Cl. 16—134)

This invention relates to hinges and particularly to concealed hinges for use on doors of refrigerators or similar structures.

Heretofore so-called concealed hinges were only partly concealed due to the fact that if entirely concealed access thereto could not be had for adjusting the hinge during assembly of a door on a cabinet. Therefore prior hinges of the so-called concealed type had portions thereof exposed exteriorly of a door or the cabinet upon which the door was mounted and these prior hinges were not truly concealed hinges.

It is one of the objects of my invention to improve the exterior appearance of refrigerators and particularly refrigerator cabinets of the household type.

Another object of my invention is to provide an improved hinge for a refrigerator cabinet door.

Another object of my invention is to provide an improved concealed hinge for a refrigerator cabinet door which is adjustable through a wall of the door.

A further object of my invention is to provide a hinge which is entirely concealed partly within the walls of a refrigerator cabinet and partly within the refrigerator cabinet door and which can be adjusted without dismantling parts of the cabinet or door to thereby facilitate alignment of the door with the cabinet door opening and to permit removal of the door in case the same should become damaged.

In carrying out the foregoing objects the invention includes other objects which consist in the details of construction, and in novel arrangements and combinations of parts to be hereinafter more fully set forth and claimed.

In describing the invention in detail reference will be made to the accompanying drawings forming a part of this application and wherein like characters denote corresponding parts in the several views in which—

Fig. 1 is a perspective view of a refrigerator cabinet having my invention embodied therein;

Fig. 2 is an enlarged fragmentary sectional view taken on the line 2—2 of Fig. 1 showing a portion of the hinge of the present invention;

Fig. 3 is an enlarged fragmentary view showing the refrigerator cabinet door in an open position and partly broken away to illustrate the adjustment of a hinge constructed in accordance with my invention; and

Fig. 4 is a vertical sectional view taken along the line 4—4 of Fig. 1 showing the refrigerator cabinet door hinges partly in sectional and partly in elevation.

Referring to the drawings, for illustrating the present invention, I have shown in Fig. 1 thereof a refrigerator cabinet 10 including insulating walls 11 bounded by metallic members 12 and 13 (see Fig. 2). The insulating walls 11 surround a food storage compartment 14 provided in the cabinet 10 and the metal members 12 and 13 are secured to a heavy metal supporting bracket 15 located at the front of the cabinet inwardly of member 13. The food storage compartment 14 is provided with an access opening 16 which is closed by a door 17. The metal member 12 forms a liner for the walls of compartment 14 and the member 13 forms the finished exterior walls of the cabinet 10. These walls 12 and 13 may be coated with vitreous enamel or any other suitable coating or finish material. The metal liner 12 terminates at the front of the cabinet in a reversely curved flange 21 and has a plurality of spaced apart straight narrow portions 22 extending outwardly therefrom. The metal member 13 is shaped to fit around the metal support 15 and an edge portion 23 thereof is located under the narrow extensions 22 on member 12. An insulating washer 24 is placed between the overlapping portions 22 and 23 of members 12 and 13 respectively to break the metal-to-metal contact thereof adjacent the door opening 16. A screw 25, having an outwardly flanged metal strip 26 located under its head, is threaded into the heavy metal support 15 to thereby rigidly secure the members 12 and 13 to the support bracket 15 at the front of the cabinet 10. A trim strip or mold member 27 of a resilient material such, for example, as rubber has a curved slot 28 provided therein and which slot receives the curved edge 21 of liner 12. The rubber trim strip 27 also has a groove provided therein for the reception of the outwardly flanged portions of metal strip 26 which extends around the door opening 16. The resilient trim strip 27 is first locked upon the liner 12 by inserting the curved edge 21 of the liner into the slot 28 of the strip 27. The groove provided in trim strip 27 is then spread apart and snapped over the flanged metal strip 26 to secure the strip 27 in position upon the cabinet so that the same forms walls of the food compartment door or access opening 16. Heavy metal cups 31 and 32 (see Figs. 3 and 4) are located beneath the cabinet exterior finish wall 13 above and below the door opening 16 respectively of compartment 14 and are welded or otherwise rigidly secured to the supporting member 15. Cups 31 and 32 are vertically aligned near one side of the opening 16 and within a portion of the cabinet front wall which is bulged outward.

ly to match the exterior bulged contour of door 17. It will be noted that the portion of exterior metal wall 13 of cabinet 10 which is bent inwardly toward the opening 16 of compartment 14 and the corresponding portion of support member 15 are provided with registering openings 33 aligned with the open end of cups 31 and 32. The cups 31 and 32 form a stationary bearing portion or member of each of a pair of hinges 10 to be hereinafter more fully described.

The door 17 of the refrigerator cabinet 10 comprises an outer metal pan 35 and an inner metal pan 36 which form a chamber therebetween for the insulation 37. Outer door pan 35 has an angular inwardly turned portion 38 terminating with a lip edge 39. A plurality of relatively narrow metal pieces 41 are welded or otherwise rigidly secured to and in spaced apart relation along the sides of portion 38 of pan 35 and extend inwardly therefrom to a point to space the pans 35 and 36 apart a desired or predetermined distance. Each piece 41 includes a flat portion 42 and an inwardly directed flanged portion 43. The flange 43 of each metal piece 41 provides a backing for the inner door pan 36 and this pan is secured to the flange 43 by a plurality of screws 44. It will be noted that the peripheral edge of pan 36 is curved as at 45 and that this curved edge overlaps and engages an edge of a rubber or the like trim strip 46. This trim strip 46 abuts the flat portion 42 of metal piece 41 and has a groove 47 cut therein for receiving the lip edge 39 of the inwardly turned part 38 of pan 35. The lip edge 39 of pan 35 and the curved edge 45 of pan 36 locks the trim strip 46 in position on the door 17. Trim strip 46 has an integral extended portion 49 which terminates in the form of a flexible hollow bead 51. The bead 51 and portion 49 of trim strip 46 abut and may, if desired, be glued or cemented to the in-turned portion 38 of outer door pan 35. The bead 51 on strip 46 is normally of a substantially D-shape and engages a flat portion 52 provided on the cabinet outer metal wall 13. Bead 51 is compressed between the cabinet wall and the door to form a seal for closing the door opening 16 to prevent escape of cold air from the food storage compartment 14 of the refrigerator cabinet 10. It will be seen that strip 46 therefore serves as a combined seal and trim or mold member.

Prior to assembling the door 17 into a unitary structure as shown in Fig. 2 of the drawings a pair of cast metal members 55 and 56 are welded, in vertical alignment with one another, to the inner face of the flat angularly disposed inturned portion 38 of pan 35. The one cast member or hinge portion 55 is located at the top of the door 17 while the other member or hinge portion 56 is located at the bottom of the door. Each cast metal member 55 and 56 forms a part of the hinge of the present invention and is hollowed out as at 57 to provide a vertical opening therethrough. Each cast member 55 and 56 has a hinge bolt 58 located within the opening 57 thereof and each of these bolts 58 is provided with a plurality of straight horizontal rack-like threads 59 extending from one end thereof throughout a part of their length. The plain end of bolt 58 in the upper casting 55 extends through an opening provided in the top edge of the door pan 35 and through openings 33 provided in cabinet wall 13 and support 15 into the upper metal cup or stationary hinge bearing portion 31. The plain end of bolt 58 in the lower casting 56 likewise extends through the wall of

door 17 and the cabinet wall 13 into the lowermost metal cup or stationary hinge bearing portion 32. A hardened steel ball 61 is disposed between the end of the lowermost bolt 58 and the closed end of cup 32 (see Fig. 4) and this ball serves to permit free swinging of door 17 about its hinges or pivotal mounting. It will be noted that each metal casting 55 and 56 has a relatively large horizontal hole 62 drilled therethrough and that this hole also extends through the inturned portion 38 of door pan 35 for a purpose to be hereinafter more fully described. Another somewhat similar horizontal hole 63 is also drilled through castings 55 and 56 and through portion 38 of door pan 35 and has a pin 64 located therein. Pin 64 is forcibly driven into hole 63 and past the threads 59 on bolt 58 to deform a part of these threads and thereby wedge the pin between the bolt and the castings 55 or 56. The drive fit of pin 64 with the threads 59 of bolt 58 locks the bolt to a casting 55 or 56 and prevents movement thereof relative to the casting. Thus bolts 58 rotate within the cups or bearing portions 31 and 32 of the concealed hinge structure when the door 17 of cabinet 10 is moved about its pivotal mounting to open or close the food compartment access opening 16. The weight of the door 17 rests upon the apex of ball 61 and this construction prevents binding of the door during movement thereof.

Having described the construction of the improved concealed hinge I will now describe the method of adjusting same to permit assembly of the door 17 upon the refrigerator cabinet. The door 17 may be assembled into a unitary structure as shown in Fig. 2 of the drawings prior to being mounted upon the cabinet 10. When it is desired to mount the door 17 upon the cabinet the resilient bead or seal portions 51 of rubber strip 46 is flexed away from the portion 38 of door pan 35 to permit access to the openings 62 and 63 located thereunder along one edge of the door. I have provided a pinion wrench or the like 65 (see Fig. 3) which is then inserted in opening 62 from outside walls of door 17. A bolt 58 is inserted into each of the castings 55 and 56 and the wrench 65 extending horizontally through the castings is rotated to cause teeth 66 provided thereon to engage and thread upon the threads 59 of the bolts. The bolts 58 may be projected through the top and bottom edges of door 17 by wrench 65, into the projected position thereof shown in Fig. 3 of the drawings, to permit movement of the door into a position to align the projecting ends of bolts 58 with the openings 33 and cups or bearings 31 and 32 on the cabinet. Thereafter further rotation of the wrenches 65 will move the bolts 58 further outwardly of door 17 and into the cups or bearings 31 and 32. When the proper vertical alignment of door 17 and its seal 51 with the door or food compartment access opening 16 has been obtained a pin 64 may be forcibly driven into hole 63 in each casting 55 and 56. The pins 64 slightly deform the portion of bolts 58 aligned with the opening 63 and lock the pins to the bolts and to the castings to prevent movement thereof relative to one another. The wrenches 65 are then removed from the openings 62 and the seal portion 51 of strip 46 is permitted to flex back against the portion 38 of door pan 35 to cover and conceal the openings 62 and 63 along the one edge of the door. The door 17 has therefore now been mounted in a pivotal manner upon cabinet 10 by means accessible through an exterior wall of the

door. Obviously all parts of the hinges are concealed beneath the cabinet walls and door walls but certain of the concealed parts are accessible through an exterior wall of the door should the hinges need adjustment to re-align the door 17 with the opening 16 after continued use has caused wear of parts. Access to the adjustable parts of the hinges can be had without dismantling the door should it be necessary to re-
move and replace the door. If the door is to be removed the pins 64 can be driven outwardly of the openings 63 in castings 55 and 56 or entirely therethrough and wrenches 65 applied to bolts 58 through openings 62 to move the bolts 15 out of engagement with their bearings 31 and 32.

From the foregoing it will be seen that I have provided an improved hinge structure for a refrigerator cabinet door member or the like that is truly a concealed hinge and yet accessible to 20 permit removal of the door from the cabinet member. My improved hinges are adjustable without danger of marring the refrigerator cabinet and door exterior finished metal walls. The improved hinges are simple in construction, 25 strong and of low cost and permit the exterior appearance of the refrigerator cabinet to be greatly improved.

While the form of embodiment of the invention as herein disclosed, constitutes a preferred 30 form, it is to be understood that other forms might be adopted, all coming within the scope of the claim.

What is claimed is as follows:

A hinge structure for pivotally mounting a 35 door upon a door frame construction, said hinge

structure comprising a bearing element secured to the door opening frame construction, said hinge structure also comprising a bolt carrying element secured to the door, a bolt associated with said bolt carrying element and projecting outwardly from the door into said bearing element, said bearing element being located inwardly of the wall surface of the door opening frame construction and the bolt carrying element and said bolt being located inwardly of walls of the door to conceal said elements of said hinge structure, means located inwardly of walls of said door engaging said bolt and said bolt carrying element for locking said bolt in a predetermined position relative to said carrying element, an 15 end portion of said bolt engaging the bearing element whereby said bearing element supports the door solely through said bolt to maintain the door in alignment with walls of the opening of the door frame construction, means providing access through a wall of the door to said locking means, 20 means for releasing same from said bolt to permit adjustment of the bolt relative to its carrying element, means providing access through a wall of the door to said bolt by a tool adapted to engage and hold said bolt in substantially said predetermined position thereof during the act of releasing said bolt locking means, and the bolt engaging tool being operable while said bolt is released to adjust the bolt relative to its carrying element for moving the door and changing its position of alignment with respect to walls 25 of the opening of the door frame construction.

EDMUND F. SCHWELLER.
